Attorneys.

UNITED STATES PATENT OFFICE.

GEORGE S. STUART, OF WASHINGTON, DISTRICT OF COLUMBIA.

FOLDING-SEAT ATTACHMENT.

1,325,423.

Specification of Letters Patent.

Patented Dec. 16, 1919.

Application filed May 17, 1919. Serial No. 297,743.

To all whom it may concern:

Be it known that I, GEORGE S. STUART, a citizen of the United States, residing at Washington, District of Columbia, have invented certain new and useful Improvements in Folding-Seat Attachments; and I do hereby declare the following to be a full, clear, and exact description of the invention, such as will enable others skilled 10 in the art to which it appertains to make and use the same.

My present invention relates to improvements in folding seat or shelf attachments for use as attached to or in connection with 15 bath tubs, beds, or other articles of furniture, and is also adapted to be attached to walls, shelves, or tables, where it is desired to provide a folding seat or shelf which may be conveniently brought into use or put 20 out of the way as may be desired.

My invention comprises more especially a wooden box, preferably rectangular in cross section for convenience of manufacture, open at the lower side or bottom into 25 which open side of the box the supporting legs and various other parts hereinafter mentioned are folded away when not in use.

My invention will be more fully understood after reference to the accompanying 30 drawings, in which like parts are indicated by similar reference symbols throughout the several views, and in which:—

Figure 1 is a perspective view showing the folding seat as attached to a bath tub.

Fig. 2 shows a section along the line 2—3 of Fig. 1, and looking to the right.

Fig. 3 shows a similar section to Fig. 2, except that the seat is in the lowered or closed position; and

Fig. 4 is a perspective view showing the device attached to a bed.

Referring first to Figs. 1 to 3, A represents a bath tub mounted on suitable feet a and provided with the usual overhanging 45 curved rim a^o .

B represents the box which constitutes the body portion of the seat or shelf which is preferably made of wood, rectangular in form as shown, and provided with a flat 50 top b , the two sides b' , having hand slots b^o , and the end pieces b^2 and b^3 .

The bottom of the box is open as shown in Fig. 2. The sides of the box are also cut away, as at b^5 , to engage the rim a^o of the 55 bath tub, and into this cut away portion b^5 the coil spring C projects, one of whose

ends c is secured to the corresponding side b' of the box, and the other end c' engages the outer face of the bath tub, as shown in Fig. 2, when the seat is in the raised position.

The legs D are hinged to the sides of the box, as at d , and are provided with downwardly projecting adjustable members D' , slotted as at d^2 to engage the clamp screws d' . The opposite legs D are connected together by the brace D^2 , and extending from one side of this brace D^2 is the cord or chain E, whose free end terminates in a button e which rests in the countersunk seat b^4 in the top b of the box B.

To the opposite side of the brace D^2 the spring F is attached, which tends to swing the legs outward to the supporting position, as shown in Figs. 1 and 2. In order to 75 limit the inward travel of the legs, and also to brace the sides b' of the box, I provide strips G, as shown in Figs. 2 and 3.

The legs D may be provided, if desired, with foot rest or auxiliary shelf H, hinged thereto, or connected therewith, in any convenient way.

Rubber cushions I may be secured to the bottom edge of the sides b' of the box B to prevent the same from rattling against 85 or scarring the sides of the bath tub when the parts are in the closed position shown in Fig. 3.

In the arrangement shown in Fig. 4, the shelf is provided with hooks K adapted to 90 engage over the end rail m of the bed M, but it will be obvious that these hooks may be applied to the opposite end rail m' or to the side rails m^2 .

The operation of the device shown in 95 Figs. 1 to 3 is as follows:

The parts being in the lowered position as shown in Fig. 3, suppose it is desired to raise the shelf to the position shown in Figs. 1 and 2, place one or both hands in 100 the hand slots b^o and swing the seat up to the horizontal position. The spring F will swing the legs to the vertical position shown in Fig. 2 and the cord E will prevent the legs from being swung too far outward. 105 The foot rest may be raised to the position shown in Fig. 2, or may be left down, as desired, but this foot rest may be done away with altogether.

If the legs are too long or too short, the 110 length may be adjusted by means of the clamp screws d' , and the adjustable feet

D', but it will only be necessary to adjust the legs once for a single installation as applied to a tub, bed, or the like.

The coil spring C will also tend to throw the seat to the horizontal position, and this spring will also serve as a lock to keep the seat from being accidentally detached from the tub when the seat is in the lowered position as shown in Fig. 3.

- 10 In order to remove the seat from the tub it will be sufficient to bend down the coil spring until it becomes disengaged from the edge of the curved rim a^o of the bath tub, and then swing the seat upward to the left 15 until the coil spring is entirely disengaged from the rim of the tub. Thus, this coil spring serves as a lock to hold the seat to the tub and at the same time facilitates the lifting of the seat when it is desired to use the 20 same.

In order to restore the parts to the position shown in Fig. 3, press the legs D backward and pull on the button e, at the same time pressing down on the box B. The parts 25 may then be swung to the position shown in Fig. 3. If the foot rest H is in the open position shown in Fig. 2, this should be swung to the closed position before swinging the box down.

- 30 If desired, and if the height of the tub permits, the legs D may be shoved under the bottom of the tub as the seat is swung to the lowered position, without the necessity of swinging the legs to the position shown in 35 Fig. 3.

The device may be operated without the use of the cord E if desired, but I prefer to have such a cord as it facilitates the operation of the device.

- 40 In the arrangement shown in Fig. 4, the parts are substantially the same as shown in the other figures, except that the seat is provided with hooks K, and the parts may be swung to the closed position as before described, then assuming the position shown 45 in Fig. 3 parallel to the height of the bed or the legs may be swung inward slightly and the parts swung under the bed out of the way.

50 While I have shown the arrangement as attached to a tub, or a bed as typical instances, it will be obvious that the same may be attached to a shelf, or sink, or wall, or porch rail, or the like, without material 55 change in form or operation, and thus a convenient swinging seat or shelf may be provided which may be thrown readily into use and also readily moved to the inoperative position and out of the way.

- 60 It will be obvious that various modifications might be made in the herein described apparatus, and in the details of construction which could be used without departing from the spirit of my invention; and I do not 65 mean to limit the invention to such details

except as particularly pointed out in the claims.

Having thus described my invention what I claim and desire to secure by Letters Patent of the United States is:—

70 1. A folding seat adapted for use with bath tubs having a flanged rim curved to form an arch in cross section, comprising a rectangular box open at the bottom and having its sides cut away to fit over said rim, coil springs secured at one end to the cut away portions of the sides of said box and having their free ends bear against the sides of said tub, and their coiled portions projecting up into the arch in the rim of the bath 75 tub, a pair of legs pivoted to the inner side of the cut away sides of said box, and adapted to be swung about their pivots and to be masked in said box, a brace connecting said legs, a cord secured at one end to said brace 80 and having the other rove through the top of said box, and a spring also connected to said brace and normally tending to swing said legs to the position for supporting said seat, substantially as described.

90 2. A folding seat adapted to be used with a bath tub provided with a flanged rim curved to form an arch in cross section, comprising a rectangular box open at the bottom and having its sides cut away to fit over said rim, with hand holes provided in the sides of said box, a pair of legs pivoted to the inner side of the cut away sides of said box, and adapted to be swung about their pivots and to be masked in said box, a brace 95 connecting said legs, a cord secured at one end to said brace and having the other end rove through the top of said box, and a spring also connected to said brace and normally tending to swing said legs to the position for supporting said seat, substantially as described.

100 3. A folding seat adapted to be used with a bath tub provided with a flanged rim curved to form an arch in cross section, 110 comprising a rectangular box open at the bottom and having its sides cut away to fit over said rim, said sides being provided with hand holes therein, coil springs secured at one end to the cut away portions of the sides 115 of said box and having their free ends bear against the sides of said tub, and their coiled portions projecting up into the arch in the rim of the bath tub, and a pair of legs pivoted to the inner side of the cut away 120 sides of said box, and adapted to be swung about their pivots and to be masked in said box, substantially as described.

125 4. A folding seat adapted to be used with a bath tub provided with a flanged rim curved to form an arch in cross section, a rectangular box open at the bottom and having its sides cut away to fit over said rim, coil springs secured at one end to the cut away portions of the sides of said box and 130

having their free ends bear against the sides of said tub, and their coiled portions projecting up into the arch in the rim of the bath tub, a pair of legs pivoted to the inner 5 side of the cut away sides of said box, and adapted to be swung about their pivots and to be masked in said box, a brace connecting said legs, a cord secured at one end to said brace and having the other rove through the top of said box, and a spring also connected 10 to said brace and normally tending to swing said legs to the position for supporting said seat, substantially as described.

GEORGE S. STUART.
